UNITED STATES PATENT OFFICE.

GEORGE H. RYAN, OF TAUNTON, MASSACHUSETTS, ASSIGNOR TO L. A. ROUNDS, OF SAME PLACE.

WIRE-NAIL MACHINE.

SPECIFICATION forming part of Letters Patent No. 309,255, dated December 16, 1884.
Application filed January 7, 1884. (No model.)

To all whom it may concern:

Be it known that I, GEORGE H. RYAN, of Taunton, in the county of Bristol and State of Massachusetts, have invented an Improved 5 Machine for Making Wire Nails and Tacks, of which the following is a specification, reference being had to the accompanying drawings, making a part hereof, which show one of my improved machines—

10 Figure 1 being a central longitudinal section; Fig. 2, a plan. Fig. 3 is a side view showing the gripping-dies and the lever for forcing them together. Fig. 4 is a side view showing the feed mechanism.

15 Machines for making nails and tacks from wire or wire-like strips of metal have long been in use; and they consist, essentially, of a feeding device for feeding the wire forward, step by step, according to the length of nail

20 desired, a pair of gripping-dies, which open just before the wire is fed between them and which close upon and grip the wire and hold it firmly, a pair of cutters which cut off the wire at the proper distance from the gripping dies, 25 and a header, the blow of which upsets that part of the wire which projects from the dies and forms a head. A clearer is also used, whose function is to strike the finished nail and knock it clear of the wire in case the cutters should not have completely severed it, this clearer operating while the wire is held by the gripping-dies just after the cutters have operated and just before the header is thrown forward.

30 My invention relates mainly to the heading mechanism and incidentally to the feeding mechanism; and it consists in causing the header to strike two blows on each nail instead of but one, as heretofore.

35 Inasmuch as wire nails and tacks vary in diameter and also in the amount of stock desirable in the head, it is necessary to nicely regulate the force of the blow given by the header to suit the size of wire used, and 40 the kind of head required, and owing to this a machine well adapted to certain sizes of wire is almost wholly unfit for use on wire one size larger, and practically useless on wire two sizes larger than the machine was made

for; hence in practice a series of machines is 50 requisite—one size for wire of a certain gage and below that gage, the next size for wire of a certain larger gage and so on—the second size being over double the weight of the smallest size as these machines are usually made, 55 as the force of the blow struck by the header for wire of a certain diameter must be much more than doubled for wire of twice that diameter.

The object of my invention is to diminish 60 the force of blow requisite in heading the nails, and thereby not only adapt a given size of machine for much larger wire than heretofore, but also to improve the heads of the 65 nails, for I have found by experience that two comparatively light blows of the header on each nail will do the work done by one heavy blow and do it better.

In order to get more time for the double blow of the header, I have altered the feeding mechanism and have also so timed the mechanism by which the gripping-dies are operated as to cause them to grip the wire for a larger portion of each revolution of the machine than heretofore.

75 Many of the parts of the machine shown are old and well known, except as above indicated, and will not be described except in so far as their description is needed to a clear understanding of my invention.

80 In the drawings, A represents the frame; B, the header-slide, and C its spring.

F represents the clearer.

H H' represent the cutter-levers; h² h³, the cutters, and h⁶ h⁷ the cutter-cams.

85 The header-slide B is forced back against the spring C by means of a cam, b, which is provided with a concentric portion, b', to hold the header in its retracted position long enough to enable the wire to be fed forward the length 90 of a nail, to allow the gripping-dies to seize the wire, the cutters to sever it, and the clearer to knock the finished nail out of the way. The projection b' then releases the header-slide B, which is thrown forward by the spring C with 95 force sufficient to partially form a head on the wire held by the gripping-dies D D'. Another projection, b², on the cam b, again forces the

header-slide against the spring C, but quickly releases it and allows it to be thrown forward to make a second blow and finish the head.

It is obvious that the gripping-dies D D' must be opened and the feed take place in the same time that the projection v of the cam b is retracting the header-slide B. The lever d of the upper gripping-die, D, is hinged to its frame and is forced down by means of lever d' , 10 pivoted at d' , actuated by cam d^3 , and forced back by spring d^4 . A toggle-pin, d^5 , connects the lever d with the cam-lever d' . The shape of the cam d^3 is shown in Fig. 3, from which it will be seen that the depression by which 15 the gripping-dies are allowed to separate forms a small portion only of the periphery of the cam, the concentric part of which holds the dies together.

For the purpose of nicely adjusting the face 20 of the gripping-dies in relation to the cutters, so as to cause the exact amount of metal required for the head to project, I have mounted the gripping-dies in a frame, I, movable on the main frame A but capable of being rigidly 25 secured to the main frame A, by means of screw-bolts $i\ i$ and screw i' . The holes in the main frame through which the bolts $i\ i$ pass are elongated to permit the requisite movement; as is also the hole in the ear of frame I through 30 which screw i' passes. A wedge, i^2 , is inserted between the frame I and the main frame A and adapted to be adjusted by means of a screw, i^3 , and nut i^4 . On loosening the bolts $i\ i$ and screw i' and properly adjusting the wedge i^2 , 35 the frame I, and consequently the dies D D', may be moved toward or from the cutters h^2 to accurately determine the amount of metal left between the cutters and the dies for forming the head of the nail. It is desirable that 40 the stress of the lever d should be such as to tend to keep lever d in place, and for this reason the toggle-pin d^5 is so inclined as to allow for the requisite adjustments of the gripping-dies and still retain its bracing position.

45 I do not claim the combination of header, gripping-dies, and mechanism for adjusting the

gripping-dies toward and from the header. The feed-cam J operates the usual feed-carriage, j , in one direction and a spring, j^2 , operates it in the opposite direction under control of the cam J. The feed-carriage j is of the usual construction and slips readily over the wire when moved by the spring j^2 , but 50 grips the wire and feeds it along when moved by the cam J. 55

It will be obvious that any suitable feed may be used if properly timed with relation to the gripping-dies.

The header-cam b has heretofore been upon the shaft h^4 , which carries the cutter-cams h^6 55 h^7 , and has consequently been placed between the cutter-cams, and it has therefore been usual to make these cams in one piece. In my machine I make the header-cam b independent of the cutter-cams and place it on a 60 separate shaft, b^4 . This enables the header-cam b to be made much wider than is possible when it is placed between the cutter-cams h^6 h^7 .

For the purpose of keeping the cutter-levers 70 in their correct positions I use conical bushings h^5 on the trunnions of the cutter-levers, these trunnions being made conical to fit the bushings, so that the wear is readily taken up by simply adjusting the bushings. 75 These bushings fit closely in their holes and are held in place by set-screws, as shown.

What I claim as my invention is—

In a machine for making nails and tacks 80 from wire, the combination of the header, the feed, the clamping-dies, and the cutters with a cam having a concentric portion to hold the header back while the wire is fed forward and the cutters sever the finished tack, and projections to operate the header twice for each 85 operation of the feed and cutters, substantially as described.

GEO. H. RYAN.
